(57) **CLAIM**

The ornamental design for a bread baker, as shown and described.

DESCRIPTION

FIG. 1 is a perspective view of a bread baker, showing the new design;

FIG. 2 is a front view of the design shown in FIG. 1.

FIG. 3 is a side view of the design shown in FIG. 1.

FIG. 4 is a top view of the design shown in FIG. 1.

FIG. 5 is a bottom view of the design shown in FIG. 1.

FIG. 6 is a perspective view of the cover of the bread baker of FIGS. 1-5, shown separately to show aspects of the design that are not visible when combined with the base;

FIG. 7 is a front view of the design shown in FIG. 6.

FIG. 8 is a side view of the design shown in FIG. 6.

FIG. 9 is a top view of the design shown in FIG. 6.

FIG. 10 is a bottom view of the design shown in FIG. 6.

FIG. 11 is a perspective view of the base of the bread baker of FIGS. 1-5, shown separately to show aspects of the design that are not visible when combined with the cover;

FIG. 12 is a front view of the design shown in FIG. 11.

FIG. 13 is a side view of the design shown in FIG. 11.

FIG. 14 is a top view of the design shown in FIG. 11; and, FIG. 15 is a bottom view of the design shown in FIG. 11.
